L. DANIEL

CAPPED NAIL AND TACK

Filed Nov. 21, 1921

INVENTOR:

Lewis Daniel

BY *Alcear Allen*

ATTORNEYS.

UNITED STATES PATENT OFFICE.

LEWIS DANIEL, OF NEWPORT, KENTUCKY, ASSIGNOR TO CLARENCE J. RENNEKAMP,
OF CINCINNATI, OHIO.

CAPPED NAIL AND TACK.

Application filed November 21, 1921. Serial No. 516,613.

To all whom it may concern:

Be it known that I, LEWIS DANIEL, a citizen of the United States, and a resident of Newport, in the county of Campbell and 5 State of Kentucky, have invented certain new and useful Improvements in Capped Nails and Tacks, of which the following is a full, clear, and exact description, reference being had to the accompanying drawings, 10 forming part of this specification.

My invention relates to nails and tacks which have secured thereon caps or button heads, which nails and tacks are used in various instances where it is desired to provide a button for a fastener, or the like.

It is the object of my invention to provide such an article which can be inexpensively manufactured, and which possesses the desired characteristics of appearance and 20 strength necessary for a marketable product of the nature set forth.

In the manufacture of special heads, such as buttons and the like for nails, the manufacturing cost enters very largely into consideration. In the past, to place a suitable button on the end of a nail or tack required operations of trimming and drilling, which required special manipulation of the small pieces making up the completed article, and 30 while this could be automatically done in large part, it required expensive machinery and considerably more time for each piece than was truly economical.

According to my invention, the pieces used 35 are stamped out and without trimming, dropped onto the usual headed tack or nail of commerce and clamped into place.

These objects I accomplish by that certain 40 construction and arrangement of parts to be hereinafter more specifically pointed out and claimed, wherein a very economical manufacturing process may be employed.

In the drawings,

Figure 1 is a side elevation of a completed 45 button headed tack.

Figure 2 is a like view of the tack before the cap is placed thereon.

Figure 3 is a perspective view of the simplest 50 form of bell used in making the cap.

Figure 4 is a perspective view of the top piece of the cap.

Figure 5 is an elevation of a nail with a double flanged button thereon.

Figure 6 is a perspective view of the double bell used with the article shown in 55 Figure 5.

Figure 7 is a perspective view of the two heads of the double button or cap.

Figure 8 is a perspective view of a small barbed nail, such as is used in making the 60 article shown in Figure 5.

Figure 9 is a perspective view of the parts of a third form of nail.

Figure 10 is a central longitudinal section through the parts shown in Figure 1. 65

Referring first to the simpler form of capped tack, it will be noted that I employ the tack 1 having the usual head 2, which as in the usual form of tack is formed by a die operation on the piece of wire forming the 70 tack.

Such tacks are the usual article of commerce and purchasable at a low price or readily manufactured by fully automatic machinery, at a high rate of speed. 75

I provide a metal stamping having a bell-like shape as at 3, and split lips 4 at the expanded end, with the apex of the bell formed with a hole 5 to slip over the shank of the tack. I also provide a top piece of flat body 80 6 and a flange 7, which in the original piece extends downwardly from the body.

In assembling the article, the tack is dropped into the bell on a suitable multiple unit machine with the head lying within the bell, which is of a size at the base of the lips to snugly receive it. The top piece is then dropped onto the assembly and pressed down and the flange turned under, which forces the head of the tack firmly into the 90 seat of the bell and engages the head around the lips of the bell, drawing said lips together snugly around the head of the tack.

The article is then complete, except for 95 enameling, if desired, and there are no parts to be injured by baking the articles after dipping in enamel.

The entire button thus formed is quite low and perfectly tight, and hammer blows on the top piece will not injure the assembly as the head of the tack itself receives these 100 blows and relieves the bell of any strain.

There are no parts to be trimmed or smoothed off, as the only edges exposed are formed by bending the metal of the top piece and bell around their respective forms.

5 In making the double button head for a nail or tack, I employ a nail having a shank 8 and head 9, same being again a cheap article of commerce. I then form a double bell having a body 10 and lips 11, 11, at each end, 10 which turn outwardly from the tubular or body portion of the double bell.

15 I also provide two end pieces similar to the one top piece of the first modification, as at 12 and 13, the end piece 12 having a hole therein to slip over the shank of the nail.

20 In assembling the article, the bell and the lower end piece 12 are first placed together and the end piece crimped over the lips of the bell by folding inwardly the flange 12^a thereof. The nail is then dropped into the other end of the bell with the shank passing through the hole in the piece 12.

25 The top piece 13 is then dropped on and driven down and the flange folded in as at 13^a. The head of the nail is thus firmly seated in the upper end of the bell where the lips start to swell and the folding or crimping in of the flange of the top piece 30 holds the lips firmly around the head.

35 Here again the head of the nail takes the blows necessary for driving down the article and there is no trimming of parts necessary to effect a finished article of great strength and perfect smoothness at all exposed or working surfaces.

40 In addition to the double bell formation in making up the capped nail, I may also proceed as follows: (Figure 9),—

45 The nail 14 with the head 15 is used as in the second instance, and the bell or fitting has a tubular body 16 with lips 17 at the lower end, but cylindrical or substantially so at the top. The cap 18, similar to the caps already described, is crimped over the head of the nail with its inner edge not quite meeting the nail shank below the head. The lower cap 19, similar to the piece 12, is crimped over the lips 17 and the nail forced down through the body 16, and the hole in the cap 19. This will force the upper edge of the body 16 into the space between the flange and head of the cap 18 and the shank of the nail, and will hold 55 the structure tightly together.

60 The expanding of the metal adjacent the nail head and the proportionate size of the tubular body and the cap 18 are arranged so that the forcing of the nail downwardly into the said body will make the tight fit last above noted.

65 It is obvious that by confining the size of the head of the tack or nail used, and likewise controlling the size of the body portion of the bell as distinguished from

the lips thereof, I can make up a capped nail or tack with the desired amount of depth from the shoulder formed on the shank of the nail to the top of the cap or button.

70

Having thus described my invention, what I claim as new and desire to secure by Letters Patent, is:—

1. In combination with a headed tack or nail or the like, a piece having split outwardly curved edges, said piece being adapted to slip over the shank of the tack or nail, and a top piece adapted to cover the top of the said head, and engage over the split edges of said first mentioned piece. 75

2. In combination with a headed tack or nail or the like, a piece having a body portion of tubular nature expanded at the upper end to form a seat for the head of said tack or nail, with a portion of the piece extending below said seat to form the shank of a button, and a top piece having a flange thereon, said piece being adapted to engage over the head of said tack or nail, with the flange bent inwardly around it to engage 90 the expanded edges of the first mentioned piece.

3. In combination with a headed tack or nail or the like, a means for forming a button thereon, comprising a piece having a 95 tubular body, and a bell-shaped crest, with the lips forming said bell-shaped crest providing a seat for the head of the nail or tack, and a top piece shaped to fit smoothly over the said head and having a flange 100 adapted to engage over the said lips and clamp said first mentioned piece firmly in position, as and for the purpose described.

4. In combination with a headed tack or nail or the like, a means for forming a 105 double headed button thereon, comprising a piece having a tubular body, and a cap secured thereon at its lower edge with said body formed out to form a seat for the head of the nail or tack, and adapted to 110 slide into position over the shank of the same, and a top cap adapted to engage over the head of the tack and firmly engage over the formed-out portion of the first mentioned piece. 115

5. In combination with a headed tack or nail or the like, a means for forming a double headed button thereon, comprising a tubular piece having expanded upper and lower edges, said expanded edges being split 120 to form lips, an apertured cap adapted to slide over the shank of the tack or nail, said cap being provided with a flange turned inwardly over the lower expanded edges of the above mentioned piece, and another cap adapted to fit over the head of the tack or nail and having a flange adapted to be turned inwardly beneath the head, and over the upper expanded edges of the first mentioned piece. 130

6. In combination with a headed tack or nail or the like, a means for forming a double headed button thereon, comprising a piece having a tubular body and cap secured thereon at its lower edge, with said body adapted to slide into position over the shank of the nail and abut the sides of the head thereof, and a top cap adapted to engage over the head of the nail having a flange formed inwardly under the head and 10 engaging over the upper end of the tubular body.

LEWIS DANIEL.
